UNITED STATES PATENT OFFICE.

FRANK WARTHER, OF CINCINNATI, OHIO, ASSIGNOR TO THE CRANE AND BREED MANUFACTURING COMPANY, OF SAME PLACE.

CAP FOR BURIAL-CASKET LIDS.

SPECIFICATION forming part of Letters Patent No. 680,092, dated August 6, 1901.

Application filed April 18, 1901. Serial No. 56,446. (No model.)

To all whom it may concern:

Be it known that I, FRANK WARTHER, a citizen of the United States of America, and a resident of Cincinnati, in the county of Hamilton and State of Ohio, have invented certain new and useful Improvements in Caps for Burial-Casket Lids, of which the following is a specification.

This invention relates to certain improvements in burial-caskets, and more particularly to such caskets as are provided with caps or cover-plates for covering and protecting the glass plates of the lids; and the object of the invention is to provide for such caskets a simple and inexpensive means for holding the caps or cover-plates securely in place, but capable of ready operation to release the same when it is desired to uncover the glass.

The invention consists in certain novel features of the construction, combination, and arrangement of the several parts of the improved cap or cover-plate retaining or holding means, whereby the device is made simpler, cheaper, and is otherwise better adapted and more convenient for use, all as will be hereinafter fully set forth.

The novel features of the invention will be carefully defined in the claim.

In the accompanying drawings, which serve to illustrate my invention, Figure 1 is a partial plan view showing a casket having a cap or cover-plate provided with my improved securing means. Fig. 2 is an enlarged fragmentary section showing one of the securing devices in detail. Fig. 3 is an under side or inverted plan view showing the parts seen in Fig. 2. Fig. 4 is an enlarged fragmentary and inverted perspective view showing one member of the improved securing means.

As seen in the views, 1 indicates the lid of the casket, having a glass plate 2 at its head end, and 3 indicates a cap or cover-plate applied over said glass plate to cover and protect the same in a well-known way. The cap or cover-plate 3 is formed with a metal frame extended around its edges, and said frame 4 is adapted to fit down flush upon the top surface of the lid 1 when in place thereon, as shown in Fig. 2.

The frame of the cap or cover-plate carries at suitable points, as indicated in dotted lines

in Fig. 1, studs or pins 5, extended down from its under side and adapted to take into sockets produced in the lid 1, said sockets being, as herein shown, formed from open-ended sections 8 of metal tubing let into the casket-lid at suitable points to receive said studs or pins 5 and having their inner walls rounded or expanded, as shown at 9, at their upper ends, so as to permit the pins or studs 5 to more freely enter the sockets. The lower ends of the sections or sockets 8 are extended down below the under side of the casket-lid 1 and are free therefrom, being provided in their side walls with longitudinal slits or kerfs 10, extended upward from their lower ends and having the portions of their walls between said slits formed into elastic tongues, which are bent slightly toward each other, so as to reduce the bores of the sections or sockets at 70 their lower ends. The studs or pins 5 are of greater length than the sockets in which they are engaged, and at their lower ends said studs or pins are formed with enlargements or heads 6, the under sides of which are made rounded, 75 as shown at 7, so as to facilitate the entry of the studs into their sockets. The said heads or enlargements 6 at the lower ends of the studs produce annular shoulders extended around the studs and adapted when said 80 studs are in place in their sockets 8 for engagement with the lower edges of the tongues of the sockets or sections 8 between the slits 10, by which means the studs or pins are held against removal from the sockets except by 85 the application of sufficient draft upon the cap or cover-plate 3 to insure the outward flexing of said elastic tongues to permit the shoulder on the stud to pass above the lower edges of the said elastic tongues. The shoulder of the stud and the lower end of the bore of the socket or section 8 will of course be made rounded, so that when draft is applied to the cap or cover-plate the stud will ride up in the bore of the socket 8. By this means 90 the cap or cover-plate is securely held upon the casket-lid against accidental displacement and is also prevented from rattling about, and when it is desired to still further guard against removal of the cap or cover-plate an auxiliary securing device is provided, herein shown in the form of a screw 95 100.

11, carried by the cap-frame 4 and adapted to be engaged with an interiorly-threaded socket 12, carried by the casket-lid 1, in such a way as to prevent the studs or pins 5 from 5 being withdrawn from their sockets until said screw shall have first been turned to disengage it from the casket-lid. The upper part of the screw above the cap 3 also forms a convenient handle, by means of which the cap or 10 cover-plate may be lifted when it is desired to remove it from the casket.

The improved securing means constructed as above described is of a very simple and economical nature and is especially well 15 adapted for use, since it permits of securely holding the cap or cover-plate upon the casket-lid and is capable of very ready operation by merely pressing the said cap or cover-plate down upon or drawing it up from the casket- 20 lid, so that delay in applying or removing the cap, such as is caused by the operation of screws and other similar devices, is avoided.

It will also be obvious from the above description that the device is capable of some 25 modification without material departure from the principles and spirit of the invention, and

for this reason I do not wish to be understood as limiting myself to the precise form and arrangement of the several parts herein set forth.

Having thus described my invention, I claim—

In a securing means for the caps or cover-plates of caskets and the like, the combination of a cap-frame having a downwardly-extended stud the lower end of which is formed with a rounded enlargement, and a casket-lid having a tubular socket-piece open at its upper end to receive said stud, the lower end of said socket-piece being extended below the 40 under side of the casket-lid and having longitudinal slits in its side walls forming between them elastic tongues for engagement with the enlarged lower part of the stud to hold the stud in place in said socket-piece, 45 substantially as set forth.

Signed at Cincinnati, Ohio, this 15th day of April, 1901.

FRANK WARTHER.
